UNITED STATES PATENT OFFICE.

EDWARD T. HESS, OF IRONDEQUOIT, NEW YORK.

AUTOMATIC GASOLINE-VENDING MACHINE.

Application filed October 16, 1926. Serial No. 142,014.

This invention aims to provide a simple coin controlled mechanism for a dispensing pump of the sort used in handling gasoline and other liquids. The invention aims, 5 further, to improve generally and to enhance the utility of devices of that type to which the invention appertains. My invention is particularly useful in places where automobiles pass since one of the machines may 10 be placed in position and it is not necessary that there should be an attendant in order to supply the gasoline to those who need it. All that is necessary, is for the customer to 15 deposit a coin in the slot and operate the machine to get a predetermined quantity of gasoline.

It has been my purpose to make such a vending machine of simple construction which will operate easily, accurately and efficiently.

With the above objects and numerous others in view, the invention resides in certain novel features of construction and in the combination and arrangement of parts 25 as will be hereinafter more fully described and claimed.

In the drawing:

Figure 1 is a sectional elevation with the cover removed of my improved coin control 30 apparatus,

Fig. 2 is a transverse horizontal section taken therethrough,

Fig. 3 is a detail view showing one pawl and the latch associated therewith,

Fig. 4 is a detail perspective view of one 35 of the pawls.

Referring to the drawing in detail, it will be seen that 5 designates the pump casing and the mechanism adapted to be disposed 40 therein may be of any ordinary or preferred form and operable through the vertical movement of lift bar 6 which has rack teeth 7 on one end thereof. A casing 8 is mounted on the casing 5 in any suitable manner 45 and has a removable cover plate 9 forming one side wall thereof. The lift rack bar 6 is slidable through the casing 8 and extends thereabove. A coin chute is indicated by the numeral 10 and has an exterior entrance 50 indicated at 11 so that a coin of the proper size may be inserted therein. An adjustable stop bar 12 is mounted on the lower portion of the bar 6 by means of a set screw 13 and may be set to stop the upper movement of 55 the lift bar 6 depending upon the amount of gasoline which should be delivered in ac-

cordance with the size of the coin. This will have to be adjusted from time to time owing to the difference in the price of gasoline from time to time. A U-shaped member 14 has 60 its leg portions slidable through openings in the coin chute 10 so that it may pass transversely there-across. On the center of the bight portion of the U-shaped member 14 there is fixed a shank 15 which extends 65 through an opening in one end of the casing and terminates in a knob 16. A spring 17 is disposed about the shank 15 impinging against the casing 8 and against knob so as to hold the U-shaped member 14 normally 70 in abutment with the inner surface of said one end of the casing. A coin impeding member 18 is pivoted in the casing and extends into the coin chute 10 and is normally held thus extended by a weighted end 19. A 75 similar member 20 is pivotally mounted in the casing below the member 18 and to the other side of the chute and also extends into the chute and is normally held in such a position by a weighted end 21. In the chute 80 between the members 18 and 20 there is located a permanent magnet 23. An operating shaft 24 is journaled transversely in the casing and on the outer end has an operating crank 25. A gear 26 is fixed on the shaft 85 24 and meshes with the teeth of the rack bar 6. A pawl 27 is pivoted intermediate its ends within the casing in the upper portion thereof and a pawl 28 is pivoted in the casing intermediate its ends in the lower 90 portion thereof. A link 29 is pivotally engaged with the pawl 27 and has a pin and slot connection with the pawl 28. A spring 30 normally urges the pawl 28 to engage with the gear 26 to prevent its rotation in a clockwise direction. A pin 31 extends laterally from the pawl 27 and a plate 32 extends laterally therefrom in an opposite direction. A latch lever 33 of the bell crank type is pivoted in the upper portion of the 100 casing and has a rod 34 pivotally engaged therewith and extending upwardly through an opening in the top of the case. An arm 34' is mounted on the upper end of the rod 6 and when the rod 6 moves downwardly it 105 will engage the rod 34 for rocking the bell crank lever or latch 33. This latch 33 has a notch 35 to engage the pin 31. A spring 36 engages the catch 33 to urge it to an engaging position at all times and also engages the pawl 27 to urge it to an engaging 110 position with the gear 26. The bell crank

catch 33 is pivoted on a bracket 37 which has slots 38 therein for receiving screws 39 so that said screws may be loosened and the brackets adjusted vertically so that the catch 5 33 may be properly disposed.

The parts are normally disposed as shown in Figure 1 and the coin is dropped in the chute 10. This coin will engage first with the member 18 and will be retarded thereby 10 so as to pass slowly by the magnet 23 which will be strong enough to hold a spurious coin. However, if the coin is good it will rock the impeding member 20 and stop opposite the lower leg of the member 14. The 15 knob 16 is then pushed inwardly so that the U-shaped member 14 through its lower leg pushes the coin against the lower end of a lever 41 which is pivotally mounted in the casing and will engage the plate 32 so as to rock the pawl 27 free from the gear 26 and allow its pin 31 to be engaged in the notch 35 of the bell crank catch 33. It 20 will thus be seen that the spring 30 will engage the pawl 28 with the gear 26. The operator may now turn the crank in a counter-clockwise direction until the rack 25 bar 6 moves downwardly so as to bring the arm 34' in engagement with the rod 34 which will cause the release of the latch 33 and allow the spring 36 to force the pawl 27 again into engagement with the gear 26 and thus the link 29 will free the pawl 28 from its engagement with the gear 26. This is so because the spring 36 works 30 through a greater leverage than the spring 30. The pin and slot connection between the link 29 and the pawl 28 allows the necessary ratcheting movement of the pawls 27 and 28. The operator may now rotate the gear 26 in a clockwise direction for lifting the rack bar and causing the gasoline to flow out in the usual well known manner. If the coin is spurious and is stopped by the magnet 23 it will be seen that when the knob 16 is pushed inwardly the U-shaped member 14 through its upper leg will push the coin from the magnet 23 out of the chute so that it will be unable to operate in a proper manner as indicated above.

50 It is thought that the construction, operation, utility and advantages of this invention will now be clearly understood by those skilled in this art without a more detailed description thereof. The present embodiment of the invention has been disclosed in detail merely by way of example since in actual practice it attains the features of advantage enumerated as desirable in the statement of the invention and the above description. It will be apparent that changes in the details of construction and in the combination and arrangement of parts may be resorted to without departing from the spirit or scope of the invention as hereinafter 55 claimed or sacrificing any of its advantages.

Having thus described my invention, what I claim as new is:—

1. A device of the class described, including in combination, a rack bar, means for mounting the rack bar for rectilinear motion, a gear meshing with the rack bar, means for operation of the rack bar, a pawl, yieldable means for normally urging the pawl into engagement with the gear, a second pawl, yieldable means for normally urging the second pawl into engagement with the gear, a link between the pawls, a pivotal connection between one pawl and the link, a pin and slot connection between the other pawl and the link, the first yieldable means being more effective than the second yieldable means, a coin chute, a lever pivotally mounted and having one end engageable with the first pawl, a push adapted to extend into the coin chute to push a coin into engagement with the lever for rocking said lever to rock the first pawl to disengage it from the gear and bring the second pawl into engagement therewith and means for holding the first pawl in its disengaged position while the rack bar completes a stroke in one direction.

2. A device of the class described, including, in combination, a rack bar, means for mounting the rack bar for rectilinear motion, a gear meshing with the rack bar, means for operation of the rack bar, a pawl, spring means for normally urging the pawl into engagement with the gear, a second pawl, spring means for normally urging the second pawl into engagement with the gear, a link between the pawls, a pivotal connection between the first pawl and the link, a pin and slot connection between the second pawl and the link, the first spring means being more effective than the second spring means, a coin chute, a lever pivotally mounted and having one end engageable with the first pawl, a push member adapted to extend into the coin chute to push a coin into engagement with the lever for rocking said lever to rock the first pawl to disengage it from the gear and bring the second pawl into engagement therewith, and latch means associated with said first pawl to hold it in a disengaged position from said gear.

3. A device of the class described, including, in combination, a rack bar; means for mounting the rack bar for rectilinear motion, a gear meshing with the rack bar, means for operation of the rack bar, a pawl, spring means for normally urging the pawl into engagement with the gear, a second pawl, spring means for normally urging the second pawl into engagement with the gear, a link between the pawls, a pivotal connection between the first pawl and the link, a pin and slot connection between the second pawl and the link, the first spring means being more effective than the second spring

means, a coin chute, a lever pivotally mounted and having one end engageable with the first pawl, a push member adapted to extend into the coin chute to push a coin into engagement with the lever for rocking said lever to rock the first pawl to disengage it from the gear and bring the second pawl into engagement therewith, latch means associated with said first pawl to hold it in a disengaged position from said gear, and means on said rack bar for releasing said latch.

4. A device of the class described including, in combination, a rack bar, means for mounting the rack bar for rectilinear motion, a gear meshing with the rack bar, means for operation of the rack bar, a pawl, yieldable means for normally urging the pawl into engagement with the gear, a second pawl, yieldable means for normally urging the second pawl into engagement with the gear, a link between the pawls, a pivotal connection between the first pawl and the link, a pin and slot connection between the second pawl and the link, the first yieldable means being more effective than the second yieldable means, a coin chute, a lever pivotally mounted and having one end engageable with the first pawl, a push member adapted to extend into the coin chute to push a coin into engagement with the lever for rocking said lever to rock the first pawl to disengage it from the gear and bring the second pawl into engagement therewith, latch means associated with said first pawl to hold it in a disengaged position from said gear, means on said rack bar for releasing said latch, an adjustable stop on said rack bar to limit the motion thereof in one direction, impeding members in the coin chute, a magnet located in the coin chute between the impeding members, and means on the push member for forcing a spurious coin from engagement with the magnet and out of the coin chute.

5. A device of the class described including, in combination, a rotatable member, means for operatively connecting the rotatable member with a pump mechanism or the like, a gear rotatable with the member, means for operating the member, a pawl, yieldable means for normally urging the pawl into engagement with the gear, a second pawl, yieldable means for normally urging the second pawl into engagement with the gear, a link between the pawls, a pivotal connection between one pawl and the link, a pin and slot connection between the other pawl and the link, the first yieldable means being more effective than the second yieldable means, a coin chute, a lever pivotally mounted and having one end engaged with the first pawl, a push member adapted to extend into the coin chute to push a coin into engagement with the lever for rocking said lever to rock the first pawl to disengage it from the gear and bring the second pawl into engagement therewith, and means for holding the first pawl in its disengaged position while the gear rotates a predetermined amount.

6. A device of the class described including, in combination, a rotatable member, means for operatively connecting the rotatable member with a pump mechanism or the like, a gear rotatable with the member, means for operating the member, a pawl, yieldable means for normally urging the pawl into engagement with the gear, a second pawl, yieldable means for normally urging the second pawl into engagement with the gear, a link between the pawls, a pivotal connection between one pawl and the link, a pin and slot connection between the other pawl and the link, the first yieldable means being more effective than the second yieldable means, a coin chute, a lever pivotally mounted and having one end engaged with the first pawl, a push member adapted to extend into the coin chute to push a coin into engagement with the lever for rocking said lever to rock the first pawl to disengage it from the gear and bring the second pawl into engagement therewith, and means for holding the first pawl in its disengaged position while the gear rotates a predetermined amount.

In testimony whereof I affix my signature.

EDWARD T. HESS.
